UNITED STATES PATENT OFFICE.

GEORG LENART, OF BONN-ON-THE-RHINE, AND PAUL LENART, OF DARMSTADT, GERMANY.

GRINDING MACHINE FOR OIL, VARNISH, AND OTHER PAINTS.

Application filed November 13, 1922. Serial No. 600,729.

To all whom it may concern:

Be it known that we, DR. GEORG LENART, a citizen of Hungary, residing at 222 Bornheimer St., in the city of Bonn-on-the-
Rhine, Germany, and PAUL LENART, a citizen of Hungary, residing at 27 Grafen St., in the city of Darmstadt, Germany, have jointly invented a new and useful Grinding Machine for Oil, Varnish, and Other Paints, of which the following is a specification.

Our invention relates to paint-grinding machines for powdering oil and varnish paints and other paints. With these machines it has been customary to have a rotary grinding disk

15 moving opposite a stationary grinding disk with a certain speed, the powdered paint being carried away by the use of stripping knives. It has been customary to feed the goods to be ground by means of a funnel.

20 In consequence of the low viscosity of the material to be ground and on account of its glueyness while being drained from the machine, the efficiency of these machines is comparatively very low. An attempt could

25 be made to increase the efficiency of the machine by increasing its rotary speed, but this attempt would be bound to fail, principally because the resistance of the ground material would increase, being accumulated by its in-

30ertia.

The object of this invention is to overcome these troubles by constructing the grinding machine in such a way that it is made part of a centrifugal pump, or by constructing 35 a centrifugal pump, which is a grinder at the same time. It is a known fact that centrifugal pumps can handle heavy liquids easily. This is due to the fact that the material to be pumped is sucked up automatically and that it is thrown by centrifugal

40 force into a pipe of constantly increasing size. According to our invention grinding disks will be arranged to take the place of the pump wings of both the pump housing

45 and the centrifugal wheel. The pulverized and liquid pulp forming the oil or varnish paint will be ground by the disks and thrown out centrifugally. Our improvement may be applied to both one faced and two faced 50 centrifugal pumps, in the latter case two opposed grinding disks operating and rotating opposite two stationary grinding disks, of the housing.

55 In consequence of the high velocity required for centrifugal pumps in addition to

the friction required for the grinding, the amount of heat developed will be comparatively large. In order to reduce this heat, the housing of the centrifugal grinding mill may be cooled correspondingly, as well as 60 the rotor.

In order to obtain an even efficiency, it will be necessary, to have an adjustable spring or weight govern the pressure of the grinding disks against one another.

In the accompanying drawing the mechanism is illustrated. Fig. 1 is a plan, Fig. 2 is a longitudinal section, and Fig. 3 a side elevation.

The frame 1 carries two bearings, 2 and 3, also the housing 4 of the centrifugal pump, whose left half 6 is pivoted at 5, and which is held tight by the swing bolts 7. On the inside a grinding disk 10 has been provided, which may be removed for repair 70 or renewal. The centrifugal wheel 8 is keyed to the hollow shafting 9, being supported by two bearings 2 and 3, the face of the rotor opposite the outer casing 6 being lined, as well as its cooperating surface with 75 an interchangeable grinding disk 11. A helical spring 12 has been provided in order to press the two grinding disks together. One end of this spring bears against the ball bearing collar 13 of the hollow shaft. The 80 other end bears against a sleeve 14 clearing the shaft 9 and provided with a male thread, the bearing 3 forming the nut 15. The tension of the helical spring 12 may be altered by screwing the sleeve 14 out of or into the 85 nut 15. The left half of the housing 6 has been made hollow for cooling purposes and has been provided with a water inlet 16 and an outlet 17. The rotor 8 may also be made hollow for cooling purposes. In this case 90 the drive shaft may be made hollow and provided with a system of pipes connected to an inlet 19 and discharge 20. The lines 19 and 20 may be separated from one another and from the hollow shaft by any suitable 95 packing.

The material to be ground is admitted through the inlet 22 and is sucked up by a set of wings of ordinary design, visible in Figs. 2 and 3, and partly protruding into 105 the inlet 22. The ground material is carried away through the discharge pipe 23 of constantly increasing size, as is customary in all centrifugal pumps.

By fitting the pulp grinder into a centrifu-

gal pump or by designing a centrifugal pump, which acts as a pulp grinder at the same time, we obtain a higher efficiency with the same grinding disk diameter, in comparison to other designs. The power consumed per hour will be slightly larger in this machine than in other designs, but the efficiency will increase many times in comparison.

10 Claims.

1. In a triturating and homogenizing machine for paints, a casing, a plurality of relatively moving cooperating friction surfaces within said casing, yieldable means 15 tending to maintain said surfaces in mutual contact, a centrifugal pump within said casing for drawing in the paint to be treated and impelling it between said friction surfaces against the resistance of said yieldable 20 means, and auxiliary means for cooling said friction surfaces.
2. In a triturating and homogenizing machine for paints, a casing, a plurality of relatively moving cooperating friction surfaces 25 within said casing, yieldable means tending to maintain said surfaces in mutual contact, a centrifugal pump within said cas-

ing for drawing in the paint to be treated and impelling it between said friction surfaces against the resistance of said yieldable 30 means, and chambers for a cooling medium adjacent said friction surfaces.

3. In a triturating and homogenizing machine for paints, a rotatable head, cooperating friction surfaces on the casing of the 35 machine and on said rotatable head respectively, centrifugal pump impellers arranged on said rotatable head in radial relation to the axis thereof, said pump being in advance of said friction members relative to 40 the incoming liquid, a shaft for rotating said rotatable head, a chamber for a cooling medium in said head, and means for circulating the cooling medium therein comprising influent and effluent passages in said 45 shaft.

The foregoing specification signed at Cologne, Germany, this 18th day of October, 1922.

DR. GEORG LENART.
PAUL LENART.
